ATTORNEY

UNITED STATES PATENT OFFICE.

JACOB M. ZOOK, OF ZOOKS CORNER, PENNSYLVANIA.

TOBACCO-LATH HOLDER.

1,116,966.

Specification of Letters Patent. Patented Nov. 10, 1914.

Application filed October 28, 1913. Serial No. 797,729.

To all whom it may concern:

Be it known that I, JACOB M. ZOOK, a citizen of the United States, residing at Zooks Corner, in the county of Lancaster and State of Pennsylvania, have invented certain new and useful Improvements in Tobacco-Lath Holders, of which the following is a specification, reference being had therein to the accompanying drawing.

My invention relates to a device for holding a lath on which tobacco stalks are hung in harvest time, and to hold the lath while the stalks are being stripped from them.

The object of the invention is to provide a device that shall be cheap, durable and efficient; and by the use of which both time and labor may be saved.

With these and other objects in view, my invention consists in certain construction and combination of parts as will hereinafter be fully described and claimed in the annexed specification, and illustrated in the accompanying drawings, which form a part of this application, and in which like figures of reference refer to corresponding parts in all of the views; but it is fully understood that while I have here described my invention as shown, that I do not confine myself to the exact design, as slight changes may be made in the construction and arrangement of the several parts without departing from the spirit of the invention.

In the drawings: Figure 1, is a side elevation of the device mounted on a table or bench, and showing a lath in place; the side being partly broken away to show the retaining part. Fig. 2, is a top plan view of the same. Fig. 3, is a front end elevation, and shows the method of removing the lath after the tobacco has been removed therefrom.

Referring to the drawings, the device comprises the base plate 1, which is provided with the attaching pin 2, for attachment to a bench or table top 22, or wagon body. To the upper side of the base plate 1, and near one end thereof is attached the side plate 3, which is formed with the bevel

end 4. To said side plate 3, is attached by the bolts 5, the side plate 6, which is spaced therefrom by the collar 7, placed on the bolts 5; said side plate 6, is also beveled at 8, and does not extend down to the base plate 1, but is spaced therefrom as shown in Fig. 1, but less than the width of a lath. Between said side plates 3, and 6, is mounted a retaining pawl 9, on the bolt 10. The lath 11, is inserted between the beveled ends 4, and 8, and is engaged by and retained from being pulled out by the retaining pawl 9.

When the tobacco stalks 12, have all been removed from the lath 11, said lath 11, is turned sidewise, as shown in Fig. 3, and is thus removed through the space between the lower edge of the side plate 6, and the base plate 1, without having to operate the pawl 9. It will thus be seen that the device is very simple and eliminates all springs, levers or hinges which are employed in other devices for this purpose.

Having thus described my invention, what I claim as new, and desire to secure by Letters Patent is:—

1. The combination in a tobacco lath holder, of a base, a side plate secured thereto, a second side plate secured to the first side plate and spaced from said side plate and said base, a swinging lath-retaining pawl mounted between said side plates and adapted to engage the upper edge of a lath inserted between said side plates.

2. In a tobacco lath holder of the class described, a pair of side plates secured together in a spaced relation, a base secured to one of said side plates and spaced from the other side plate, and a lath-retaining pawl pivoted between said plates for the purpose set forth.

In testimony whereof I affix my signature in presence of two witnesses.

JACOB M. ZOOK.

Witnesses:

JOHN J. THOMPSON,
WM. J. COULTER.
